CARTON

Frank A. Marx, Bridgetown, Ohio, assignor to
The Richardson Taylor-Globe Corporation,
Cincinnati, Ohio, a corporation of Ohio

Application July 14, 1942, Serial No. 450,874

2 Claims. (Cl. 229—44)

This invention relates to a collapsible carton and is particularly designed for use as a tobacco carton of the type heretofore usually manufactured of tin or similar metal and comprising a body formed with a hinged top.

An object of the invention is to provide a carton of this type comprising the advantages of the tin box or carton and other advantages not possessed by the latter, such as cheapness and efficiency of manufacture, light weight, collapsibility for shipment, etc.

Another object is the provision of a carton of this kind which possesses ample strength and rigidity so as to remain intact and serviceable during any period of normal use.

These and other objects are attained by the means described herein and illustrated in the accompanying drawing, in which:

Fig. 1 is a plan view of the blank out of which the carton of this invention is formed, the score lines in this and other views being indicated by dotted lines and cuts being indicated by full lines.

Fig. 2 is a perspective view of a completed carton in closed position.

Fig. 3 is a cross-sectional view on the line 3—3 of Fig. 2.

Fig. 4 is a perspective view of the completed carton with the top in open position.

Fig. 5 is a plan view of the carton in collapsed position, just prior to complete flattening.

Fig. 6 is a cross-sectional view on the line 6—6 of Fig. 5.

In greater detail and with reference to the drawing:

A carton of this invention is formed of an elongated blank which is cut and scored to provide an inner rear wall 10 and an inner side wall 11 joined thereto along a score line 12. An inner front wall 13 is joined to side wall 11 along score line 14. Another inner side wall 15 joins the inner front wall 13 along the score line 16. An intermediate rear wall 17 is joined to the inner side wall 15 along score line 18 and outer side wall 19 is joined, along score line 20, to the wall 17 and to the wall 19 is connected the outer front wall 21, along a score line 22. Another outer end wall 23 is joined to the outer front wall along the score line 24 and, finally, an outer rear wall 25 joins the side wall 23 along the score line 26.

The intermediate wall 17 and the outer front wall 21 are each provided with closure flaps 27—28 and 29—30, respectively, and the outer side walls 19 and 23 are formed with closure tabs 31—32 and 33—34, respectively. These flaps and

tabs, it will be noted, are cut clear at their ends for independent hinge action. The wall 17 is scored adjacent the top and bottom, as indicated at 35 and 36, along the hinge lines of said closure flaps. Wall 17 is further scored at 37 for defining, along with the score line 35, one of the rear elements 38 of a hinged closure, as will be further described. The side elements of the said hinged closure are indicated at 39 and 40 (Fig. 1).

10 The outer front wall 21 and the outer side walls 19 and 23 are cut through, as indicated at 41, 42 and 43, the cut 43 being contiguous at one end with the score line 37 of the wall 17 and the cut 42, at one end, being contiguous with a score line 49, the latter being provided adjacent the top of the outer rear wall 25.

The blank so formed and cut is initially laid out flat, as seen in Fig. 1. The underside of the wall 10, as seen in Fig. 1, may have a glue strip 44 applied thereto. The wall 10 is now bent along the score line 12 over upon the inner end wall 11 and the inner front wall 13. The doubled parts just mentioned are now carried over by bending along the score line 16 and disposed against the intermediate wall 17 and the glue strip 44 fastens the inner rear wall 10 to the intermediate wall 17.

In this connection a novel manufacturing detail may be described, namely, the notch 45 provided at the top of said wall 10 in alignment with the glue strip 44. If this portion of wall 10 were not notched, the glue strip, as applied by the usual mechanically operated glue wheel or the like, would extend clear to the top of the wall 10, which wall portion would therefore, upon the folding operation above described, become secured to a movable part 38 of the hinged cover to be formed, precluding operation of the latter.

The blank is now further bent along the score line 20 and again along the score line 24. The face of the outer rear wall 25, as seen in Fig. 1, has, prior to this last mentioned operation, been provided with a glue strip 46 and when the said wall is carried around to its final position against the outer face of the intermediate wall 17, it is glued thereto and likewise to the closure element 38 (Fig. 3).

The carton is now in shipping condition, as substantially indicated in Figs. 5 and 6. Obviously, the uniformity and flatness of the carton in this condition makes for cheapness and efficient packing and shipping.

It is contemplated that the carton is to be completed at the location where it is filled and subsequent to the filling. At this time, the first oper-

ation of the completion cycle is the bending up of the flattened carton to a rectangular shape. Thereafter, the bottom flaps and tabs 28-30 and 32-34 are turned in and secured by adhesive in a manner well known, as indicated in Fig. 3.

The filling operation is now performed at the top of the carton with the closure flaps and tabs 27-29 and 31-33 open for this purpose. Thereafter, these flaps and tabs are turned in and adhesively secured together similarly to the bottom parts. Needless to say, the filling operation may be performed at either end of the carton.

The completed commercial package has now been prepared except for suitable wrapping which may be provided as desired.

When the user purchases a commodity such as tobacco packed in a carton of this invention, it is merely necessary for him to bend backwardly the top portion of the carton as seen in Fig. 2 to the position seen in Fig. 4, the hinged movement being effected along the score lines 49 and 37, as seen in Fig. 3.

It will be seen that in effect the present invention provides an outer casing having a body and a hinged top and enclosing an inner casing which projects above said body to be frictionally embraced by said top when the carton is closed.

For ease in operation, the inner front wall 13 is cut at the top, along the line 47, and the adjacent corners of the side walls 11 and 15 are rounded as at 48 (Fig. 4) so that the hinged cover slips into and out of place without interference. The carton itself as well as the manufacturing

details disclosed, including the initial glueing operation above described, are believed to represent a substantial advance in the art. Modifications will suggest themselves upon consideration of the present disclosure but these are believed to be comprised within the spirit and scope of the invention.

What is claimed is:

1. In a carton, an inner wall, an outer wall overlying the inner wall, an integral hinge element formed on the outer wall, the inner wall in that portion thereof overlaid by the hinge element being provided with a notch of a depth equivalent to the width of said hinge element, and a glue strip applied to the inner wall prior to juxtaposition of said two walls and extending across said inner wall to the inner end only of said notch whereby, upon such juxtaposition, said hinge element is left free for operation relative to the inner wall.

2. The process of connecting together in overlying relationship a pair of similar-sized sections of sheet material while maintaining said sections independent along one edge portion, the process comprising making a notch across the proposed independent portion of one of said sections, applying a glue strip to the face of said one section in alignment with said notch and extending only to the inner end of the notch, and placing the glue-carrying face of said one section in aligned contact with a face of the other section of sheet material.

FRANK A. MARX.
